(57) **CLAIM**

The ornamental design for a display screen or portion thereof with icon, substantially as shown and described.

DESCRIPTION

A portion of the disclosure of this patent document contains material which a claim for copyright is made. The copyright owner has no objection to the facsimile reproduction by anyone of the patent document or the patent disclosure, as it appears in the US Patent and Trademark Office patent file or records, but reserves all other copyrights whatsoever.

FIG. 1 is a front view of a display screen or portion thereof with icon in a first embodiment; and,

FIG. 2 is a front view of a display screen or portion thereof with icon in a second embodiment.

The broken lines showing a display screen or portion thereof form no part of the claimed design.
